TIRE

Walter W. Hinkel, Massillon, Ohio, assignor to The Goodyear Tire & Rubber Company, Akron, Ohio

Filed June 25, 1973, Ser. No. 373,233

Term of patent 14 years

Int. Cl. D12—15

U.S. Cl. D12—142

The figure is a perspective view of a tire showing my new design, it being understood that the design is repeated throughout the circumference of the tire, the opposite side being substantially the same as that shown.

I claim:

The ornamental design for a tire, substantially as shown and described.
